MEANS FOR DRYING CORRUGATED BOARD

William R. Swanson, Toronto, Ontario, and Peter Rintoul, Fairbank, Ontario, Canada, assignors to Gair Company Canada Limited, Toronto, Ontario, Canada

Application March 20, 1939, Serial No. 262,944

6 Claims.

(Cl. 34—160)

The principal objects of this invention are to effect the rapid de-hydration of corrugated board during the process of manufacture thereof and to provide a form of mechanism which will automatically accommodate strips of various widths of board and which will require the minimum of attention.

The principal features of the invention reside in the novel form of apparatus for carrying the invention into effect whereby the corrugated strip is advanced through a drying zone or zones in which the respective edges are subjected to high and low air pressures to cause a definite travel of heated air longitudinally of the corrugations to effect the maximum moisture extraction in the minimum of time.

A further and important feature resides in the novel manner of forming enclosed pressure areas about the respective edges of the strip as it is being advanced.

Still further features of importance consist in the novel construction of a bed over which the corrugated board is passed whereby said bed is provided with perforated areas on either side communicating with air ducts arranged therebeneath, and whereby flexible means is provided to cover the corrugated board and extend beyond the edges thereof and to contact with the corrugated surface to form ducts connecting the perforations of said bed with the corrugations of the board.

In the drawing Figure 1 is a fragmentary side elevational view of an apparatus suitable for carrying this invention into effect.

Figure 2 is a fragmentary plan view of one side of the apparatus broken away in part to show a corrugated strip passing over one of the perforated suction zones.

Figure 3 is a transverse sectional elevation taken on the line 3—3 of Figure 2.

Figure 4 is an enlarged fragmentary view through one of the perforated pressure zones showing the corrugated board and overlying travelling belt.

Figures 5 and 6 are diagrammatic part structural views taken transversely of the drying table illustrating a modified manner of directing the flow of heated air in oppositional directions at spaced zones in the length of the table to achieve a more balanced drying influence.

In the manufacture of corrugated boards under present conditions considerable space is required not only to permit the adhesive to sufficiently set as it is travelling from the forming machine but also in order to provide storage space in

10 drying rooms where the finished board is required to stand for some period in order to effect final drying thereof.

The present invention has been devised to overcome these difficulties in a simple but efficient manner, and in the form of the invention shown frame members 1 and 2 are spaced apart to support a flat table section 3 which may be of sheet metal and this is dished downwardly at opposite sides to form suction and pressure chambers 4 and 5 respectively, which chambers are arranged in paired relation and extend from adjacent the outer edge portions to the intermediate portion of the table section 3.

15 A flat sheet or panel of metal 6, presenting a smooth upper surface over which the corrugated board to be dried is adapted to slide, is placed over the table section 3 and the portions overlying the suction and air chambers 4 and 5 are perforated as shown at 7 and 8 respectively. One, two or more pairs of the chambers 4 and 5 may be provided in progression, and a conduit 9 for supplying heated air has a tubular connection with each pocket 5, while a suction conduit 10 has a tubular connection with each pocket 4 and air is heated in any suitable manner and circulated under force by a suitable blower (not shown) having the pressure outlet connected with the conduit 9 by the conduit 9' and the suction inlet connected with the conduit 10 by the conduit 10'.

20 Optionally the conduit 9' may be connected with the pressure outlet of one blower to direct highly heated air to the chamber 5 while a separate blower may be provided having its suction side connected with the conduit 10' and discharged to atmosphere.

The corrugated board 11 as it comes from the forming and glueing machine advances over the upper perforated panel 6 with the corrugations extending transversely thereof so that one edge registers with the pressure chamber or chambers 5 while the other edge registers with the suction chamber or chambers 4.

25 A comparatively heavy belt or mat 12 of endless formation is so mounted and driven that its lower stretch rests on the corrugated board and by frictional engagement therewith causes the latter to move over the panel 6, the board easily sliding over the smooth surface of the latter. Such belt is of substantially greater width than the strip of cardboard so that the overhanging edge portion 12' thereof will drop downwardly and contact with the marginal portions of the upper table panel 6 at the outward side of the

perforated area and form therewith a substantial seal enclosing air chambers 13 and 14 at the respective edges of the corrugated board.

The edges of the belt 12 may be suitable weighted in order to enhance its sealing relation with the panel 6 and this may be accomplished by the use of a plurality of rollers 14' which may rest on the superimposed corrugated board and belt to confine these in close association to the panel 6 and such rollers are here shown provided with flanges 15 which bear on the edge extremities of the belt to hold the same closely to the panel 6. The rollers 14' are suitably guided and rotatably mounted in carrying brackets 16.

With the arrangement shown it will be apparent that when highly heated air under pressure is forced into the chamber 5 it will pass out through the perforations 8, which are located beyond the edge of the corrugated strip to be dried, and on entering the enclosure or pocket 13 it will be caused to flow through the transverse spaces between the corrugations in extensive surface contact with the corrugated board so that the board will be rapidly dehydrated and the adhesive firmly set.

Simultaneous with the application of heated air pressure to the chamber 5 the suction within the chamber 4 will assist in accelerating the flow of heated air through the corrugations which, on reaching the pocket or enclosure 14, will pass down through the exposed openings 7 into the chamber 4 and finally out through the conduits 10 and 10'.

It may be desirable in certain cases at least to provide a suction and pressure pocket such as 4 and 5 at each side of the drying table so that the heated air will be caused to flow first from one side of the corrugated board to the other in passing over one set of pockets and then from the said other side to the first-mentioned side in subsequently passing over a second set of pockets in order to achieve a more balanced drying of the product and in Figures 5 and 6 we have shown a suitable arrangement for this purpose.

Figures 5 and 6 represent two drying zones spaced apart in a direction longitudinally of the direction of travel of the belt 12, the pockets 4' representing suction or outlet chambers having outlets 10'', while the pockets 5' represent pressure chambers located at opposite sides of the perforated table or plate 6 in offset relation to which the dry heated air is directed under pressure through the ducts 9'', each chamber 4' being arranged transversely opposite to a pressure chamber 5' as shown.

With this arrangement it will be apparent that any tendency to dry one side of the board more than the other with a consequent tendency to warp the product will be avoided due to the balanced application of the drying air flows. Such an arrangement is particularly advantageous where the board strip is exceptionally wide.

Further structural variations may be resorted to within the essential spirit of the invention and while the present invention has been devised particularly in connection with the drying of corrugated boards, it is readily adaptable to the handling of other types of board products, and in the case of a non-corrugated product the rollers 14' may be such as to substantially clear the belt 12 intermediate of its width so that the pressure of the forced blast will substantially raise the board strip sufficiently to allow the air flow to pass between the panel 6 and board strip and/or between the board strip and belt 12.

It will be appreciated that the construction shown provides for the accommodation of various widths of strips which may be passed therethrough for drying purposes and the same belt 12 will co-operate with the various widths of strips to form the sealing pockets 13 and 14 at the edges thereof.

What we claim as our invention is:

1. Apparatus for drying corrugated board comprising a table surface over which the board to be dried is advanced in a direction transversely of the corrugations, said table surface having perforated areas extending beyond the side edges of the board, said table having sealing areas at the outward sides of the perforated areas, a flexible drive belt engaging the upper surface of the corrugated board in driving contact and having edge portions extending beyond the edges of the board over said perforated areas and having substantial sealing engagement with said sealing areas and forming with the board and table surface pressure and suction chambers respectively at the ends of the corrugations, the perforations in the table surface forming inlet and outlet passages for said pressure and suction chambers, means directing heated air to said inlet perforations from below said table surface, and means for conducting air from said outlet perforations below said table surface.

2. Apparatus as claimed in claim 1 in which said sealing areas at the outward side of the perforated areas comprise surfaces disposed below the upper level of the board with which the extending edge portions of the flexible belt are adapted to engage by downward flexing, means being provided for holding said belt edges in downwardly flexed sealing relation to said sealing areas.

3. Apparatus as claimed in claim 1 in which said sealing areas at the outward side of the perforated areas comprises surfaces disposed below the upper level of the board with which the extending edge portions of the flexible belt are adapted to engage by downward flexing, means being provided for weighting said belt including roller means extending below the upper surface of the intermediate portion of the belt and engaging the belt edges to hold the same in downwardly flexed sealing relation to the said sealing areas.

4. Apparatus as claimed in claim 1 in which said sealing areas at the outward side of the perforated areas comprise surfaces disposed below the upper level of the board with which the extending edge portions of the flexible belt are adapted to engage by downward flexing, and rollers extending transversely of said belt and resting on the intermediate portion thereof to weight the same downwardly on the board, said rollers having portions of greater diameter at the ends engaging the edge portions of the belt to hold the same in downwardly flexed sealing relation to the said sealing areas.

5. Apparatus for drying corrugated board and the like comprising a table having perforated areas at respective sides, pressure and suction chambers on the underside of the table one communicating with the perforated area of one side of the table and the other communicating with the perforated area of the other side of the table, and means for overlapping said perforated areas at opposite sides of a board overlying said table and forming with the board and with said table pressure and suction enclosures communicating with said respective chambers by way of the

respected perforated zones, said overlapping means including a conveying belt engaging in frictional driving contact with said board to advance the same over said table past the perforated zones.

6. Apparatus for drying corrugated board comprising a table surface over which the board to be dried is advanced in a direction transversely of the corrugations, said table surface having perforated areas extending beyond the side edges of the board, conveying belt means co-operatively engaging said board and overhanging the edges thereof for substantial sealing engagement with said surface beyond the perforations therein and forming with said board and surface pres-

sure and suction chambers respectively at the ends of the corrugations, the perforations in the table surface forming inlet and outlet passages for said pressure and suction chambers, means directing heated air to the inlet-forming perforations from below said table surface, and means for conducting air from the outlet-forming perforations below said table surface, said respective perforated areas extending inwardly from opposite sides of the table surface for a substantial portion of the width thereof for co-operation with boards of various width.
